METHOD OF PRODUCING A STERILE MEAT PACKAGE

Arno Brasch, Wolfgang Huber, and Adnan Waly, Brooklyn, N. Y., assignors to Electronized Chemicals Corporation, Brooklyn, N. Y., a corporation of Delaware

No Drawing. Application December 20, 1952,
Serial No. 327,176

1 Claim. (Cl. 99—174)

The present invention relates to the art of food sterilization and preservation by ionizing penetrating radiation such as high velocity electrons, for instance.

One of the objects of our invention is to use ionizing penetrating radiation, such as high voltage, high intensity electrons for instance, of limited penetrating range, for the preservation of foodstuffs to be sold in packages of such dimensions as to place a portion of the substance beyond the range of penetration of the electrons.

Yet another object is to provide a novel package for food substances to be sterilized by ionizing penetrating radiation which is well adapted to the capabilities of such sterilization processes when conducted at relatively low cost with low voltage equipment.

Still another object is to provide a novel package or packaging method to be used in conjunction with sterilization by penetrating ionizing radiation which renders such sterilization processes more efficient.

Other objects and advantages will become apparent from the following description of a preferred embodiment of our invention.

Processes are now known for the sterilization of food and other substances which involve bombarding the substance with high velocity electrons having sufficient velocity to pass through the substance, or, in the alternative, to completely penetrate the substance when it is bombarded from opposite sides so as to destroy the capability of propagation of microorganisms present in the substance. For instance such a process is disclosed in Re-issue Patent No. 23,195.

There are instances, however, where it will be desired to use penetrating ionizing radiation of comparatively low voltage for the purpose of producing sterility in certain food substances to be sold in packages larger than can be penetrated completely by the equipment available.

In the interest of better understanding the process of the present invention will be described in conjunction with the preservation and packaging of a specific food substance—ground meat. It will be appreciated, however, that the same method or minor variations thereof will apply equally well to the preservation of other substances.

As a starting point in explaining the process it will be assumed that it is desired to sterilize ground meat by electron bombardment and sell the sterilized product in packages which have dimensions of such order that the center of the package of meat is beyond the range of penetration of high velocity electrons available from a particular electron accelerator. According to the present invention, the necessary quantity of meat to be packaged within the container is sealed within a plastic sack impervious to microorganisms in such fashion that the package is airtight and has as little air space therein as is conveniently possible. The sack material should be proof against the entrance of microorganisms and for this purpose polyvinyl or polyethylene films among others are satisfactory. Also if desired, metal foils or treated

paper or the like can be used. It is preferred that after the meat substance has been placed within the package that the package be heat sealed if the package material permits this. This can be accomplished in production in an economical fashion by applying well known techniques.

These individual packages of meat enclosed within the plastic or other bags, are then pressed flat so as to have a relatively uniform predetermined thickness which is within the penetrating range of the radiation source available, or, if desired, the equipment can be so arranged as to bombard the packages from opposite sides thereby enabling thicker packages to be used.

After the packages have been subjected to electron bombardment or to other penetrating radiation having the capability of causing sufficient ionization within the substance to produce sterility, the individual packages are shaped to fit the particular container or box in which the meat substance or other food is to be marketed. For instance, the irradiated thin, plastic enclosed packages of meat can be rolled or pressed to cylindrical form to fit an ordinary tin coated sheet steel can, or, if desired, these pliable packages can be folded or otherwise shaped to a generally rectangular form so as to fit any suitable cardboard carton. Of course, two or more individual thin sterilized packages of food can be shaped so that together they fill one larger can or carton.

A specific variant of the above generally described process follows:

50 Fifty pounds or so of ground meat is taken from a cooler and is preferably deaerated and then stuffed into a tube of laminated cellophane of six-inch width. This protecting film is bacteria-proof and is substantially proof against passage of moisture and gas.

55 After packing, one end of the tube is heat sealed (this of course may be done before stuffing) while through the open end of the tube the contents is deaerated by ordinary vacuum technique, and the vacuum finally is replaced by oxygen free nitrogen.

40 The open end of the tube is then hermetically sealed, and the tube and contents are feed through cooled rollers so as to form a ribbon about six inches wide and twelve millimeters thick. This ribbon or band is fed into a beam of high intensity electrons produced by an accelerator of any suitable type, such as that forming the subject matter of U. S. Patent No. 2,429,217, for instance which has the capability of accelerating electrons to a velocity equivalent to two million volts. The apparatus is set up so that the electrons generated bombard the band from opposite faces. For the dimensions given the electrons should be accelerated to a velocity of approximately 2.1 million volts.

50 This technique and voltage will cause thorough penetration of the material by the electrons without substantial over-irradiation of any portion of the product. The bombardment treatment is continued until a sterilizing dose of 1.5×10^6 REP has been absorbed. The speed with which the material is continuously fed through the electron beam is adjusted to accomplish this, and depends, of course, upon the irradiating power of the equipment available. Preferably the intensity of the electron beam should be enough so that the sterilizing dose specified above will be absorbed without subjecting any portion of the product to bombardment for more than a few seconds. Under these conditions biological sterility is obtained throughout the meat as well as throughout the packaging material, without bringing about harmful organoleptic changes in the meat substance.

At a convenient time following sterilization, the ribbon 60 of packaged meat is squeezed together so as to separate the meat at regular intervals by bands which extend transversely of the strip. This provides continuous areas

of the packaging material which is brought together from opposite sides into face to face relationship along bands extending transversely of the ribbon. The film at these areas is then heat-sealed together. The meat within the long tube is therefore isolated into individual packages connected in series by the heat-sealed transverse bands. The tube is then cut into individual pieces along the center lines of these heat-sealed bands so as to form hermetically sealed individual packages which may, for instance, weigh one pound net each.

These individual packages are then enclosed in permanent storage containers. For instance cardboard with or without transparent windows may be used. If rough handling or prolonged storage periods are expected the material may be packed into a more rugged outer container made of wood, rigid plastic or metal for instance.

If it is desired to store the raw ground meat for an indefinitely long period, it is advantageous if the outer container is also hermetically sealed so as to prevent the slow change in humidity of the meat product which may take place through the cellophane wall. Preferably under these conditions the wall surface of the outer hermetically sealed container and the space between the inner wall of the outer container and the outer wall of the cellophane wrapped package should be sterilized and this may be accomplished in easy fashion for instance by exposing the final packaged product to a dose of high intensity electrons having a range sufficient to penetrate the outer package and the space about the inner package but not sufficient to penetrate appreciably into the meat.

Meat or other products so packed can be stored in the raw, cooked, or partially cooked state, at room temperature for indefinite periods so long as the hermetic seal of the inner wrapper is not broken.

The salient feature of the invention is that the food substance is treated in thin section which can be adequately sterilized with relatively low velocity electrons and that this thin section of the food substance is enclosed within a deformable, airtight container which is proof against the passage of microorganisms. The result is that the treatment container, any air, gas or moisture which may be within the container, and the food substance itself are all sterilized simultaneously. Recontamination of the food substance after sterilization is impossible since it is enclosed within the impervious envelope and, under these conditions, although the product eventually is to reach the market within a tin can or other protective container, it is not necessary to sterilize the interior of the exterior container.

The process may be varied by using films which are not completely impervious to the passage of microorganisms and then after irradiation, the packages can be reshaped and inserted into sterile cans which are sealed under sterile conditions, or if desired, after radiation sterilization, pliable packages such as these can simply be sealed in cans which are subsequently lightly bombarded

so as to sterilize the can, the air or other gas therein and the surface of the pliable package.

One of the great advantages of this process is that it makes it feasible to sterilize comparatively large individual packages of foods by the use of electron accelerating equipment of only five million volts capacity or even less. The process thus avoids the necessity for operating equipment at extremely high voltages in order to obtain penetration to the center of containers of ordinary size. This is important, since it involves greater difficulties and is far more costly to obtain deep penetration by sterilizing electrons than it is to obtain broad electron beams. For many products at least this process will result in the ultimate packaged sterile product being provided at less cost than would be involved if the substance were first packaged in the sheet metal can and subsequently sterilized by high voltage electrons having the necessary penetrating range to insure sterility of all the product.

Another advantage is that there is danger that small amounts of radioactive isotopes will be formed in food substances if deep penetration is attempted through the use of electrons accelerated to over ten million electron volts for instance. This danger is completely avoided by the present process.

Having described our invention, what we claim as new and useful and desire to secure by Letters Patent of the United States, is:

The process for producing a sterile package of ground meat by the use of an electron accelerator having a capability of accelerating electrons to a velocity equivalent to substantially two million volts, which comprises providing a quantity of the ground meat, sealing said quantity into a pliable container formed of a material which is impervious to the passage of microorganisms, flattening the filled ground meat package thus formed so that no portion thereof is more than substantially twelve millimeters thick, subjecting the flat package thus formed to bombardment for a few seconds from said accelerator on both faces thereof to a dose of approximately 1.5 times 10^6 REP so as to sterilize the ground meat, reshaping the package to more convenient form for handling, and enclosing the pliable package as thus reshaped in a second container more resistant to deformation than said pliable package.
